POCKET CIGARETTE MAKING MACHINE

Edward Calderio, Garfield, N. J.

Application January 25, 1934, Serial No. 708,308

11 Claims. (Cl. 131—5)

My invention relates to improvements in pocket cigarette making machines.

The primary object of the invention is to provide a device of this class having a pair of rollers and a single traveling apron adapted to be wound on the rollers, the cigarette being made in a trough formed by the apron between the rollers, as the apron passes from one roller to the other, said device being compact and simple in construction, reliable and efficient in operation and inexpensive to manufacture.

A further object of the invention is to provide a device of the above character having guard plates associated with the ends of the casing adjacent the lateral edges of the apron, which are automatically positioned with respect to the ends of the trough in the apron, when the casing is in open or closed position, to retain the tobacco in the ends of the trough and tightly and evenly pack the tobacco in the cigarette ends, while rolling the cigarette, thus forming a perfect machine made cigarette.

A still further object of the invention is to provide tension members in the sides of the casing manually operable to regulate the tension of the apron when rolling the cigarette, so as to form a tightly or loosely rolled cigarette.

Another object of the invention is to provide novel spring means for opening the casing and a spring catch for holding the casing closed.

Other objects and advantages of the invention will be apparent during the course of the following description.

In the accompanying drawing, forming a part of this specification and in which like reference numerals are employed to designate like parts throughout the same,

Fig. 1 is a side elevation view of the machine,

Fig. 2 is a longitudinal sectional view of the same, with parts broken away,

Fig. 3 is a cross section taken on line 3—3 of Fig. 2,

Fig. 4 is a cross section taken on line 4—4 of Fig. 2,

Fig. 5 is a cross section taken on line 5—5 of Fig. 2,

Fig. 6 is a horizontal section taken on line 6—6 of Fig. 1,

Fig. 7 is a fragmentary detail view of the hinge connection between the casing sections,

Fig. 8 is a detail sectional view of one of the rollers showing the connection between the roller and apron, and,

Fig. 9 is a detail side view of the roller showing

the connection between the roller and turning knob.

Referring to the drawing, wherein for the purpose of illustration I have shown a preferred embodiment of my invention, the numeral 5, denotes an elongated hollow casing, in its entirety, which is preferably constructed of a suitable composition spring material. The casing is divided longitudinally into sections 6 and 7, hingedly connected together at each end, by pivot pins 8, extending through the overlapping ears 9, projecting from the adjacent ends of the end walls 10, near the bottom of the casing. The lower edge of the end wall of section 6, is formed with an arcuate recess 11, as shown in Fig. 7, which permits the sections of the casing to swing on their pivots to an open position, the movement of the sections being limited by the shoulder 12, which abuts against the edge of the end wall of the other section. The sections of the casing are moved to open position by the U-shaped leaf spring 13, disposed intermediate the ends of the casing, which has openings 14 adjacent each end adapted to engage over the pins 15, projecting from the inner wall of each section and the ends of the spring engage beneath the projections 16 formed integral with the wall holding the spring in position and secure against displacement.

The bottom meeting edge 17, of section 6 extends beneath the bottom of edge 18 of the section 7, as shown more clearly in Fig. 4, the intermediate portion of the edge 17 being provided with spaced parallel slits 19, forming a spring tongue or catch 20, having a downwardly extending projection 21, at its free edge adapted to engage in the longitudinal slot 22, formed in the bottom of section 7, adjacent the edge 18, the projection being normally retained in the slot 22, by the raised projection 23 formed along the slot opposite the projection 21, whereby the sections are held in closed position. The strip along the bottom of section 7, between the slot 22 and edge 18 is depressible and has a raised finger piece 24 on the outside which when pressed by the finger moves the catch 20 inwardly thereby releasing the projection 21 from engagement with the slot 22 and projection 23, so that the sections are free to open under the action of spring 13.

The opposite end walls of each section, near the top, have bosses 25 formed on the inside provided with bearing recesses 26 to receive one end of the rollers 27, and the other end walls are provided with bearing openings 28, through which the opposite ends of the rollers project. The

ends of the rollers are secured in the bearing recesses 26, by U-shaped shims 29, inserted through slots 30, intersecting the recesses, into engagement with the annular grooves 31 in the rollers. The projecting ends of the rollers extend slightly beyond the ends of the sections and have turning knobs 32 fitted thereon. The rollers 27 are split longitudinally, as at 33, for the greater portion of their length, to receive 10 the ends of the apron or belt 34, which are retained therein, by beads 35 formed along the ends of the apron, which seats in the groove 36, formed along one edge of the split. The apron is constructed of suitable flexible rubberized material and is adapted to be wound on either of the rollers upon turning the knobs 32 and is of such a length that it can be projected downwardly between the rollers to form a trough to receive the tobacco. As shown in Fig. 9, a positive connection is established between the knobs 32 and rollers 27, by the rib 37 formed integral with the knob which fits in the end of the split 15 33 in the rollers.

The side walls of each section, intermediate 25 its ends, and at a point adjacent the rollers 27, has a spring tension member 38, struck therefrom which is formed by the spaced vertical parallel slots 39 and longitudinal connecting slot 40. The outside of the members 38 have finger pieces 30 41 formed integral therewith for depressing the tension members 38 into frictional contact with the apron wound on the rollers and thereby, control the tension on the apron so that the cigarette may be rolled loosely or tightly. The 35 top meeting edges of the sections are slightly spaced apart, as at 42, so as not to bind the cigarette paper inserted therein, in which the tobacco is to be wrapped.

In order to prevent any of the tobacco in the 40 trough falling over the edges of the apron and to pack the tobacco tightly in the ends of the cigarette being formed, I provide at each end of the casing guard plates 43, of substantially rectangular shape and of a width corresponding to 45 the width of the casing when closed. The lower end of the plates are pivotally mounted on the pivot pins 8 and opposite edges of the plates at the lower end thereof are provided with recesses 44 to receive the lugs 45, projecting from the 50 sides of the casing, which co-act with the recesses to center the guard plates between the sections, when the casing is open so as to cover the ends of the trough and retain the tobacco therein.

When making a cigarette, the device is held 55 horizontally in the hands, with the apron 34 wound upon the roller nearest the person. The finger piece 24 at the bottom of the casing is then depressed releasing the catch 20, so that the sections of the case, under the action of the spring 13, are moved to an open position. The apron 34 between the two rollers is depressed to 60 form a trough, in which to place the charge of tobacco for making a cigarette, and the tobacco is prevented from falling over the ends of the trough by the guard plates 43, which also tightly 65 and evenly pack the tobacco in the ends of the cigarette being formed. The amount of tobacco placed in the trough will determine the size of the cigarette and after the proper quantity of tobacco is deposited in the trough, the cigarette paper is inserted with its edge disposed between the tobacco and apron near the inner roller. The casing is then closed with the free edge of the cigarette paper projecting through the space 42 70 between the top meeting edges of the casing sec- 75

tions and is held closed by the spring catch 20 which engages in the slot 22. The apron 34 is then wound on the roller farthest from the person by turning the knob 32, which draws the cigarette paper into the device and winds it 5 snugly around the tobacco to form the cigarette. Just before the free edge of the paper enters the device the edge is moistened by passing the tongue thereover which causes the edges of the paper to adhere together, when wound completely around the tobacco. In thus forming the cigarette the apron will be wound wholly upon the roller farthest from the person and by reversing the device it is ready for rolling another cigarette. After the cigarette is formed the 15 catch 20 is released and upon movement of the casing sections to open position the apron between the rollers is drawn taut to a horizontal position which elevates the finished cigarette so that it may be easily removed from the device. 20 A tightly or loosely rolled cigarette may be formed by regulating the tension of the apron as it is unwound from the roller, which is manually controlled by depressing the tension member 38 into frictional contact with the apron on the roller, 25 their being one tension member for each roller.

From the above it is evident that the several steps of my method to make a cigarette include the forming of a loop in a flexible apron between two pivotally approachable rollers, placing the 30 tobacco in said loop and inserting the wrapper through the mouth thereof, winding the apron on one roller while unwinding it from the other, thus pulling the apron so as to roll the tobacco and wrapper into a cigarette and tensioning the 35 apron so as to cause radial compression as well as axial compression of the tobacco against the guard plates or end compression members. It is also to be noted that in my device the loop of the 40 apron is during rolling free to bulge out in all directions and that no lateral point pressures are caused by the tensioning of the apron which pressures must of necessity tend to flatten out the cigarette cylinder during rolling.

It is to be understood that the form of my invention herewith shown and described is to be taken as a preferred example of the same and that certain changes in the shape, size and arrangement of the parts may be made without departing from the spirit of the invention or the 50 scope of the subjoined claims.

Having thus described my invention, I claim:—

1. A cigarette making machine comprising a casing composed of two hinged sections, a roller journaled in each of said sections, an apron extending between and connected to said rollers, adapted to form a trough between said rollers for the rolling of a cigarette, a guard plate pivotally mounted at each end of said casing adjacent the edges of said apron, the lower end of said plates having recesses in its opposed edges, and lugs projecting from the sections of said casing engageable in said recesses adapted to center said guard plates with the ends of the trough when 60 the casing is open.

2. A cigarette making machine comprising a casing composed of two hinged sections, a roller journaled in each of the sections, an apron extending between said rollers adapted to form a 70 trough therebetween, for the rolling of a cigarette, a guard plate pivotally mounted at each end of said casing adjacent the edges of said apron and lugs integral with the sections of said casing adapted to move said guard plates when 75

the casing is opened, to center the plates with the ends of the trough.

3. A cigarette making machine comprising a casing composed of two hinged sections, a roller journaled in each of said sections, an apron extending between said rollers adapted to be wound thereon, spring tension members struck from the sides of said casing intermediate their length adapted to be moved into frictional engagement with the apron wound on said rollers to control the tension of said apron while rolling the cigarette, and spring means helping to hold said tension members out of engagement with said apron.

4. A cigarette making machine comprising a casing composed of two hinged sections, a roller journaled in each of said sections, an apron extending between and connected to said rollers, adapted to form a trough between said rollers, for the rolling of a cigarette, and spring tension members struck from the sides of said casing, centrally of their length, adapted to be moved into frictional engagement only with the central portion of the apron wound on said rollers to control the tension of said apron while rolling the cigarette.

5. A cigarette making machine comprising a casing composed of hinged sections, a roller journaled in each of said sections, an apron extending between and connected to said rollers adapted to form a trough between said rollers, for the rolling of a cigarette, a guard plate pivotally mounted at each end of said casing adjacent the edges of said apron, and spring tension members struck from the sides of said casing centrally of their length, adapted to be pressed into frictional contact only with the central portion of the apron wound on said rollers whereby the tension of the apron is regulated when rolling a cigarette.

6. The method of making a cigarette with a cigarette making machine having a casing provided with a central tension applying member substantially in the plane of the inner surface of the casing, which consists in placing tobacco in a loop formed in a flexible apron adapted to be moved beneath the tension applying member, inserting a wrapper through the mouth of said loop between the tobacco and apron, moving the apron so as to roll the tobacco and wrapper into a cigarette, allowing the loop to bulge freely laterally in all directions and applying pressure only at the tension applying member while moving the apron beneath the same.

7. In a cigarette making machine having a casing with a substantially plane surface, the combination of a pair of pivotally approachable rollers, a flexible apron extending between said rollers adapted to form a trough therebetween for

the reception of tobacco and a wrapper, end members abutting the edges of the apron, and centrally located means normally lying in substantially the same plane as the plane surface of the casing, for applying tension only to the center of said apron to cause radial and axial compression of the tobacco when rolling the same.

8. A cigarette machine comprising in combination a casing, pivotally approachable rollers mounted in said casing, an apron extending between and connected to said rollers, adapted to form a trough between said rollers, means for winding said apron on one roller while unwinding it from the other, and a central tension applying member carried by said casing adapted for applying direct pressure only to the central portion of the apron on the roller being unwound.

9. A cigarette machine comprising in combination a casing, pivotally approachable rollers mounted in said casing, an apron extending between and connected to said rollers, adapted to form a trough between said rollers, means for winding said apron on one roller while unwinding it from the other, a central tension member substantially in the plane of the surface of said casing and a projection extending outwardly from said tension member for pressing said tension member into frictional contact with the apron wound on said roller.

10. A cigarette machine comprising in combination a casing, pivotally approachable rollers mounted in said casing, an apron extending between and connected to said rollers adapted to form a trough between said rollers, means for winding said apron on one roller while unwinding it from the other, a spring tension member struck from said casing, centrally of its length, adjacent said rollers, and a projection extending outwardly from said tension member for applying tension directly to the central portion of the apron wound on said roller.

11. The method of making a cigarette with a cigarette making machine having a casing provided with a pair of rollers and a central tension applying member, which consists in placing tobacco in a loop formed in a flexible apron adapted to be wound on and unwound from the rollers, beneath the tension applying member, inserting a wrapper through the mouth of said loop between the tobacco and apron, moving the apron so as to roll the tobacco and wrapper into a cigarette, allowing the loop to bulge freely laterally in all directions and applying the tension directly to the central portion only of the apron on the roller being unwound.
